UNITED STATES PATENT OFFICE.

HORACE RESLEY, OF CUMBERLAND, MARYLAND.

IMPROVEMENT IN CAR-COUPERS.

Specification forming part of Letters Patent No. **173,343**, dated February 8, 1876; application filed September 17, 1875.

To all whom it may concern:

Be it known that I, HORACE RESLEY, of Cumberland, in the county of Alleghany and State of Maryland, have invented a new and Improved Car-Coupling; and I do hereby declare that the following is a full, clear, and exact description of the same, reference being had to the accompanying drawing, forming a part of this specification, in which—

Figure 1 is a vertical longitudinal section; Fig. 2, a plan view; Fig. 3, a vertical section, showing the use of the supplemental pin.

The invention relates to certain improvements in that class of car-couplings which operate automatically by means of a gravity-catch; and it consists in the particular construction and arrangement of parts, as hereinafter described, and pointed out in the claim.

In the drawing, A represents the draw-bar of my improved coupling, which is constructed with a central vertical longitudinal slot B, in which plays the gravity-catch C. Said catch is made with a concave face, *a*, and is provided with an open bearing, *b*, which moves around the rounded portion *c* of the draw-bar as a pivot, being guided in its said motion by the lugs *d d*, which move in circular guide ways *f f* in the draw-bar. D represents a hole in the front part of the gravity-catch, and E a second hole in the bottom of the draw-bar, which holes are arranged to register with each other, so as to receive a supplemental coupling-pin, F, of the ordinary construction. The object of this arrangement is to adapt my coupling devices to receive and secure the short links that are ordinarily used with the common form of draw-bar and coupling-pin,

so that a car provided with my coupling may not only be coupled with another provided with a similar device, but may be coupled with any of the ordinary draw-bars now in use.

In using the ordinary form of coupling-pin for short links it is necessary to elevate slightly the gravity-catch, so as to bring the holes D and E in alignment.

Upon each side of the catch C are shoulders *g g*, which rest upon the top of the specially-provided links G, to hold them in proper position to enter the mouth of the next draw-bar.

By means of the above-described arrangement is provided a very simple and effective automatic coupling, which requires but little change in the construction of the draw-bar, and which is well adapted to be used with the ordinary form of coupling.

I am aware of the fact that numerous automatic couplings have been constructed which operate upon the same general principle of my devices, and I therefore confine my invention to the particular construction and arrangement as shown and described.

Having thus described my invention, what I claim as new is—

The automatic coupling, consisting of the draw-bar having slot B, hole E, and guide-ways *f f*, in combination with the gravity-catch C, having hole D, shoulders *g g*, and guide-lugs *d d*, substantially as and for the purpose described.

HORACE RESLEY.
